(57) **CLAIM**

The ornamental design for a rolling pin, as shown and described.

DESCRIPTION

FIG. 1 is an isometric view of a rolling pin showing our new design, in which the parts of the rolling pin have been separated.

FIG. 2 is a side view thereof, with the parts separated.

FIG. 3 is a right-side end view thereof, with the parts separated.

FIG. 4 is a left-side end view thereof, with the parts separated.

FIG. 5 is an isometric view thereof, in which the parts have been assembled.

FIG. 6 is a side view thereof, in which the parts have been assembled.

FIG. 7 is a right-side end view thereof, with the parts assembled; and,

FIG. 8 is a left-side end view thereof, with the parts assembled.

The broken lines in the figures are for illustrative purposes only and form no part of the claimed design.
